UNITED STATES PATENT OFFICE

2,518,485

STAPLE EXTRACTOR

Arthur H. Maynard, Warwick, R. I., assignor, by
mesne assignments, to Bostitch, Inc., a corpora-
tion of Rhode Island

Application June 4, 1947, Serial No. 752,539

2 Claims. (Cl. 254—28)

1

This invention relates to staple-extractors for removing staples and like fasteners from papers or other articles held together thereby.

One object of the invention is to provide a small, compact device of the type indicated which may be used as a desk implement or carried in the pocket.

Another object is to provide a device of the type indicated having a pointed blade for insertion under the head or crossbar of the staple and means combined therewith and movable relatively thereto to withdraw the staple without crinkling or buckling the paper.

Another object is to provide a device of the type indicated which is more convenient to operate for extracting staples by causing their clinched legs to be straightened and withdrawn through the paper without tearing or otherwise mutilating it.

Another object is to provide a device of the type indicated which can be more readily inserted under the head of the staple and conveniently operated in one hand to quickly extract the staple.

Further objects of the invention are set forth in the following specification which describes a preferred form of construction of the device, by way of example, as illustrated by the accompanying drawing. In the drawing:

Fig. 1 is a side elevational view of the present improved staple-extractor;

Fig. 2 is a plan view of the same;

Fig. 3 is a side elevation of the device illustrating its method of operation and the relationship of its parts as the staple is withdrawn from the work;

Fig. 4 is a similar side elevation of the device illustrating the manner of inserting its cooperating blades under the head of the staple;

Fig. 5 is a greatly enlarged forward end view of the device showing the parts in position as the staple is first partly withdrawn from the work;

Fig. 6 is a similar view showing the parts of the device in position as the staple is completely withdrawn; and

Fig. 7 is an enlarged transverse sectional view on line 1—1 of Fig. 2 showing the concavo-convex form of the main blade of the device and illustrating the manner in which the movable blade nests therein when in closed relationship.

Referring to the drawing, the present improved staple-extractor comprises a main member 2 constructed from a strip of flat sheet-metal with a rearwardly-projecting, inclined handle 3 of considerable length and a tapered blade 4 projecting forwardly in horizontal relationship at its end. The blade 4 is of novel form being generally

pointed in plan view at its forward end with its sides curving rearwardly therefrom and terminating in arcuate shouldered projections 5 at the rear. As shown in the enlarged view, Fig. 7, the main or under blade 4 is shaped to concavo-convex shape in cross-section and tapered to a sharp point of extreme thinness in the vertical direction.

Mounted above the main element 2 and connected therewith to adapt it to rock relatively thereof is a finger-lever 7 having a forward blade 8 of substantially the same marginal contour as the main blade 4 with shoulders 11 and a convex under side to adapt it to seat within the concavity in the main blade. The finger-lever 7 has a relatively flat horizontal portion 9 at the rear of the blade 8 and offset upwardly thereabove which is continued rearwardly in an angular arm terminating in an arcuate portion 10 for receiving the pressure of the operator's finger.

The finger-lever 7 is rockably mounted above the main member 2 by means of a relatively flat leaf-spring 12 having its rearward end fastened to the handle 3 by hollow rivets 13, while its forward end is attached to the under side of the flat portion 9 of the lever by rivets 14. The offsetting of the flat portion 9 of the lever 7 above the bottom of the blade 8 provides a clearance space for the end of the spring 12 and the heads of the rivets, as shown in Fig. 1 of the drawing, so that the blade 8 may seat in the hollow of the lower blade 4 with the upper surfaces of both blades flush at the pointed ends. It will be observed by reference to Figs. 1 and 2 that normally the spring 12 maintains the rearward finger-portion of the lever 7 rocked upwardly and its forwardly-projecting blade 8 nested in the concavity of the lower blade 4, while permitting the lever 7 to be rocked to raise its blade 8 above the lower blade 4.

The present staple-extractor is adapted for convenient operation to withdraw staples from the work by being manipulated in the manner as next explained. The implement is grasped in one hand with the fingers enclosing the handle-portion 3 of the member 2 and the thumb resting on the upper curved end 10 of the finger-lever 7. Referring to Fig. 4, with the implement held in the hand in the manner explained it is first tilted upwardly to incline the blades 4 and 8 at a sharp angle to the work, indicated at W, to adapt the pointed ends of the two blades to be inserted under the head or crossbar of the staple s. The blades 4 and 8 are then pushed forwardly under the head of the staple s and the imple-

ment tilted downwardly to cause the blades to slowly withdraw the staple as they assume a position with the rearward portion of the blade 4 lying substantially flat against the top of the work, see Fig. 5. At this juncture the shoulders 5 on the upper blade bring up against the legs of the staple 8 as the latter is wedged or pried upwardly with respect to the work W. Some care must be exercised not to press down on the finger-lever 7 until both blades 4 and 8 have been inserted under the head of the staple and forced therethrough with the legs of the staple in position abutting the shoulders 5 on the lower blade and the corresponding shoulders 11 on the upper blade. In other words, to insure effective operation of the device both blades must be inserted under the head of the staple before the lever 7 is actuated. When this has been accomplished the curved end of the lever 7 is pressed downward to rock the top blade 8 upward into the position shown in Figs. 3 and 6, whereupon the staple will be rapidly withdrawn from the work as its legs are straightened to pass through the holes in the paper or other material. As the lever 7 is rocked to raise the blade 8 the staple will usually be forced upward with a sharp snap-action to cause it to fly into the air away from the blade 8. In this way staples can be very rapidly removed and ejected from the implement so as not to clog it for further use. Due to the fact that the legs of the staple are bent outwardly from the clinch and straightened as they ride across the lateral edges of the lower blade 4 the paper or other material is not torn, or otherwise damaged so that only the original small holes remain therein.

It will be observed from the foregoing description that the present device is of extreme simplicity comprising only two main parts, the handle-member 2 and the lever 7, with a spring for connecting them in co-operative relationship. Consequently, no pins or other pivoting means are required and the implement may be manufactured very economically by forming its parts from stampings, each completed in a single operation in a die. The spring connection between the finger-lever 7 and the main element 2 insures against looseness and play between the parts, thus maintaining them in proper registry so that the blade 8 on the lever 7 will always seat closely nested in the concavity of the blade 4 on the main element 2. In other words, the spring connection between the parts maintains the two blades 4 and 5 in alinement to insure their proper interfitting relationship, the spring having the dual function of normally holding the blades in contact and returning them to closed position when the lever 7 is released from pressure.

By constructing the lower or main blade 4 of concavo-convex form tapered outwardly toward its lateral edges a very thin point is provided at its forward end to facilitate its insertion under the head of a clinched staple with the upper nested blade not materially increasing the thickness at the point. It has been demonstrated that the blades may be inserted under the head of a staple between its legs much more easily and with less effort than in previously-used devices in which the two blade portions overlap, one on top of the other. For this reason the device is

much more convenient and practical to use, being adapted for removing staples of various sizes either composed of fine or coarse wire. It will be understood that whereas the first retracting effort is exerted slowly as the two blades are pushed through the staple, the final withdrawal is very rapid to eject the staple with a quick action, as the lever 7 is operated in the manner explained.

While the invention is herein described and illustrated as embodied in a preferred form of construction, it is to be understood that modifications may be made in the shape and structure of the parts without departing from the spirit or scope of the invention. Therefore, without limiting myself in this respect, I claim:

1. An improved staple-extractor comprising a relatively flat strip-like member forming a handle with its forward end inclined at an angle thereto and tapered to provide a pointed blade having curved marginal edges terminating in arcuate shoulders at the rear and shaped to concavo-convex form in cross-section, a finger-lever having a flat lower portion extending at an angle thereto with a blade offset downwardly from said flat portion and projecting forwardly therefrom, said blade shaped substantially to the form of the main blade, and of convex form on its under side to adapt it to seat in the concavity of the main blade, and a leaf-spring riveted to the handle of the main member at one end and extending forwardly therefrom in abutting relation to the under side of the flat portion of the finger-lever with its forward end fastened thereto.

2. A staple-extractor comprising a main member having a handle-portion with a blade projecting forwardly therefrom at an angle thereto, said blade having a pointed end tapered to extreme thinness on its marginal edge, a finger-lever comprising a main portion having an angular flat portion projecting forwardly therefrom with a pointed blade offset downwardly and projecting forwardly from the flat portion of said finger-lever, said blade on the main element having a flat lower face and a concaved recess in its upper face, the blade on the finger-lever conforming in outline to that of the blade on the main member and shaped with a convex bottom face adapted to seat in the concaved recess of the blade on the main member with its flat upper face flush with the upper face thereof, and a flat leaf-spring fastened at its rearward end to the main member and to the under side of the flat portion of the finger-lever and so constructed and arranged as to maintain the finger-lever rocked into position to hold its blade firmly seated in the blade of the main member while adapting it to be raised, thereabove by the rocking motion of said finger-lever.
